UNITED STATES PATENT OFFICE.

WALTER O. McDANIEL, OF ST. LOUIS, MISSOURI, ASSIGNOR TO SCHROETER BROTHERS HARDWARE COMPANY, OF ST. LOUIS, MISSOURI, A CORPORATION OF MISSOURI.

NUTCRACKER.

1,151,110.

Specification of Letters Patent. Patented Aug. 24, 1915.

Application filed April 17, 1915. Serial No. 22,041.

To all whom it may concern:

Be it known that I, WALTER O. McDANIEL, a citizen of the United States, residing at St. Louis, Missouri, have invented a certain 5 new and useful Improvement in Nutcrackers, of which the following is a full, clear, and exact description, such as will enable others skilled in the art to which it appertains to make and use the same.

10 This invention relates to nut crackers, and has for its main object to provide an inexpensive nut cracker of simple construction, that is efficient, strong and easy to operate, and which is so designed that nuts of various 15 sizes can be cracked in same without a preliminary adjustment of the device.

Another object is to provide a device that will crack nuts of various sizes without crushing the kernels of the nuts or pinching 20 the operator's fingers. And still another object is to provide a nut cracker that is composed of a few light-weight castings of simple 25 design that can be assembled easily and permanently connected together in such a manner that there is very little liability of the device getting out of order when it is in use.

Other objects and desirable features of my invention will be hereinafter pointed out.

30 Figure 1 of the drawings is a side elevational view of a nut cracker constructed in accordance with my invention. Fig. 2 is a vertical sectional view taken on the line 2—2 of Fig. 1. Fig. 3 is a vertical sectional view 35 taken on the line 3—3 of Fig. 2; and Fig. 4 is a perspective view of the operating lever and cam that are employed for actuating the movable jaw.

40 Referring to the drawings, which illustrate the preferred form of my invention, A and B designate two jaws which are disposed oppositely to each other and provided with a plurality of nut-receiving recesses that are adapted to receive the nuts of various sizes. The jaw A is stationary and is preferably formed integral with a base portion C on which the jaw B is slidingly mounted. A screw cam D, which is oscillatingly mounted in the movable jaw B, co- 45 operates with an inclined groove or recess 1 in the top face of the base portion C to move the jaw B toward and away from the stationary jaw A when said screw cam D is

oscillated back and forth by means of an operating lever E that is rigidly connected 55 to said screw cam. Any suitable means may be employed for connecting the base portion C to a supporting structure, but I prefer to provide said base portion with a depending hook-shaped part 2 that carries a clamping 60 screw 3, thereby enabling the device to be applied to or removed quickly from a supporting structure α , such, for example, as a table top.

The opposed faces of the jaws A and B 65 comprise vertically-disposed parallel portions 4 and inclined diverging portions 5, as shown in Figs. 1 and 3, so that the jaws will accommodate nuts of different sizes, and the means that move the jaw B toward and 70 away from the stationary jaw A is so designed that the jaw B has only a slight movement in both directions and never comes in contact with the stationary jaw A. The object of constructing the device in this 75 manner is to overcome the necessity of adjusting the device preparatory to cracking the nut. If a comparatively small nut is to be cracked, it is arranged between the jaws A and B near the lower ends of said jaws 80 and thereafter the lever E is actuated so as to move the jaw B toward the jaw A, the screw cam D that actuates the movable jaw B being so designed that it will only move said jaw far enough to crack the shell of the 85 nut without liability of crushing the kernel. After the nut has been cracked the lever E is swung in the opposite direction, so as to restore the jaw B to its former position. If a larger nut is to be cracked, it is arranged 90 between the inclined diverging faces 5 of the jaws A and B and the operations previously described are repeated.

In the embodiment of my invention herein illustrated the jaws A and B are provided 95 with a plurality of pairs of nut-receiving recesses. As shown in Figs. 1 and 3, a pair of nut-receiving recesses α are formed in the parallel faces 4 of said jaws and two pairs of nut-receiving recesses β and γ are formed 100 in the inclined diverging faces 5 of said jaws. Jaws of the construction above described center the nuts properly and hold a nut in position after the jaws have started to close, thereby enabling the operator to remove his fingers from the nut prior to the 105

completion of the cracking operation. In other words, the jaws of my improved cracker are so designed that the operator can place a nut in one or the other pairs of nut-receiving recesses in the jaws, depending upon the size of the nut, and then release the nut after the lever E has been moved a slight distance, or sufficiently to cause the jaws to clamp the nut, the operation of cracking the nut being completed by moving the lever E to the end of its stroke and thereafter reversing the lever E or moving it in the opposite direction so as to restore the movable jaw B to its normal position. The nut-receiving recesses *a*, *b* and *c* that are formed in the jaws of the device are preferably made deep enough so that the opposite ends of a nut will not contact with the bottoms of the pair of recesses in which it is arranged, thereby causing the edge portion of said recesses to exert pressure uniformly on the opposite end portions of the nut at a slight distance from the extreme ends of the nut, and thus causing the shell of the nut to crack at the center of the nut. In view of the fact that the jaw B has a fixed movement and only comparatively slight movement, there is no liability of crushing the kernel of the nut during the operation of cracking the shell. In order that comparatively small nuts may be cracked in the device, I have provided the base portion C with a nut-receiving recess *d* arranged adjacent the stationary jaw A and have provided the parallel faces 4 of the jaws A and B with serrations 6 that tightly grip a nut that is arranged in the recess *d*, and thus effectively prevent the nut from falling out of said recess. The base portion C of the device and the depending hook-shaped part 2 thereon are preferably I-shaped in cross section, and the movable jaw B is provided at its lower end with hook-shaped portions 7 that embrace the top flange of the base portion C, and thus securely hold the jaw B in an upright position on the base portion C without interfering with the sliding movement of said jaw. The thread of the screw cam D coils around the hub of said cam approximately 180°, and the groove 1 in said base portion which receives the thread of said cam has the same angle as the pitch of said thread, so as to cause the jaw B to move freely back and forth on the base portion C when the cam D is oscillated. The operating lever E can be connected to the cam D in various ways without departing from the spirit of my invention, but I prefer to connect said parts together in the manner herein illustrated, so as to simplify the device and reduce the cost of manufacturing same. As shown in Fig. 4, the lever E is provided at one end with a laterally-projecting shank whose end portions 8 and 9 are round and whose intermediate portion

10 is of non-circular shape in cross section, said shank being preferably formed integral with the lever E. The hub 11 of the cam D has a non-circular shaped bore 12, as shown in Fig. 4, that corresponds to the cross-sectional shape of the intermediate portion 10 of said shank, so as to cause said cam to turn with the lever E after the shank on said lever has been inserted through the hub of said cam. The cam D is arranged in a pocket or cut-out portion 13 in the jaw B, and the round end portions 8 and 9 of the shank of the lever E fit freely in holes of corresponding shape that are formed in the inner and outer walls, respectively, of the pocket 13 in the jaw B. It will thus be seen that the shank on the operating lever E is journaled in the jaw B and that said shank supports the screw cam D.

To assemble the parts just referred to the screw cam D is first arranged in the pocket 13 in the movable jaw and the shank on the lever E is then slipped through the hole in the outer wall of said pocket and forced inwardly through the bore in the hub of the cam D until the journal 8 at the outer end of said shank enters the opening provided for same in the other wall of the pocket 13 in the movable jaw B. Thereafter a pin or other suitable retaining device 14 is passed transversely through the hub 11 of the cam D and through the portion 10 of the shank on the lever E, so as to securely connect said cam and lever together. The hub of the screw cam D extends practically the entire length of the pocket 13 in the movable jaw B, and consequently, it will be impossible for the trunnion 8 on the shank of the lever E to slip out of its bearing in the jaw B after said cam has been connected to said shank by the retaining device 14. I prefer to make the intermediate portion 10 of the shank on the lever E and the socket 12 in the hub of the cam D slightly tapered, so as to insure a tight fit between said cam and shank after the parts have been assembled.

As previously stated, I do not wish it to be understood that my invention is limited to a nut cracker in which the operating cam and lever are connected together in the manner herein illustrated, but such a construction is exceptionally desirable, on account of the fact that a single retaining device, namely, the device 14, securely connects the cam and lever together and also retains said parts in operative position in the jaw B. If desired, the cam D of the device may be provided with stops 15 and 16 that coöperate with the base portion C to limit the rotary movement of said cam in both directions, said stops preventing the cam D from assuming such a position that the thread thereon moves out of the inclined slot 1, thus permitting the jaw B to be withdrawn from the base portion C.

My improved nut cracker comprises only four parts, namely, the base portion C, the movable jaw B, the operating lever E and the cam D, and as all of said parts can be formed from castings which are of such design that they can be assembled quickly and easily, the device can be manufactured at a very low cost. All parts of the device are large enough so that the device will be exceptionally strong and rigid, thus tending to eliminate breakage when the device is in use, the thread of the cam D is large enough and thick enough to prevent same from wearing out quickly and thus rendering the device useless, and said cam is connected to the operating lever and is arranged in the movable jaw B in such a manner that there is little danger of its getting out of order when the device is in use. Small nuts, large nuts and nuts of intermediate sizes can be cracked quickly and effectively in a device of the construction above described without liability of crushing the kernels and without the necessity of adjusting the device to accommodate the particular nut being cracked, owing to the fact that the jaws A and B of the device have a plurality of pairs of nut-receiving recesses that accommodate nuts of different sizes, and as the movable jaw and the operating mechanism for same are so designed and arranged that said jaw has a fixed movement of only slight length toward and away from the stationary jaw of the device, there is no danger of the operator pinching his fingers during the operation of cracking the nut, nor is there any possibility of the nut jumping out of position between the jaws when the jaw B is moving toward the rigid jaw A, owing to the fact that said jaws have coöperating surfaces that bite upon the end portions of the nut.

Having thus described my invention, what I claim, and desire to secure by Letters Patent, is:

1. A nut cracker, comprising opposed jaws provided with a plurality of pairs of conical nut-receiving recesses for holding nuts of various sizes, and an actuating mechanism for causing said jaws to exert sufficient pressure on a nut to crack the shell of same without crushing the kernel of the nut.

2. A nut cracker, comprising opposed jaws whose coöperating faces are provided with a plurality of alining conical recesses for receiving nuts of various sizes between same when the jaws are opened, and an operating mechanism for imparting a fixed movement of relatively slight degree to one of said jaws so as to exert sufficient pressure on the shell of the nut to crack the same.

3. A nut cracker, comprising opposed jaws having inclined diverging faces that are provided with alining conical recesses that are adapted to receive nuts of various sizes when the jaws are opened, and an op-

erating mechanism that imparts a fixed movement of comparatively slight degree to one of said jaws in a direction toward and away from the other jaw.

4. A nut cracker, comprising opposed jaws having parallel faces and inclined diverging faces that are equipped with a plurality of pairs of conical, stepped nut-receiving recesses for holding nuts of various sizes, and an operating mechanism for one of said jaws which always moves same a fixed distance, irrespective of the nut being cracked.

5. A nut cracker, comprising a stationary jaw and a movable jaw whose opposed faces are provided with stepped, conical recesses so that nuts of various sizes can be arranged between same when the jaws are opened, said movable jaw having a fixed stroke in both directions, and a manually-operated device for positively actuating said movable jaw in both directions.

6. A nut cracker, comprising a stationary base portion provided with a rigid jaw, a movable jaw slidingly mounted on said base portion, and an operating screw oscillatingly mounted in said movable jaw and having its thread arranged in engagement with an inclined groove in said base portion.

7. A nut cracker, comprising a base portion provided with a rigid jaw, a movable jaw slidingly mounted on said base portion, and an operating cam oscillatingly mounted in said movable jaw and arranged in engagement with an inclined groove in said base portion, said jaws being provided in their opposed faces with a plurality of pairs of conical nut-receiving recesses which are so arranged that they will hold nuts of various sizes when the jaws are opened.

8. A nut cracker, comprising a base portion provided with a stationary jaw, a movable jaw slidingly mounted on said base portion, the opposed faces of said jaws comprising parallel serrated portions and inclined diverging portions provided with conical recesses that are adapted to receive nuts of various sizes when the jaws are opened, a screw cam oscillatingly mounted in said movable jaw and arranged with its thread in engagement with an inclined groove in said base portion, said thread extending around the hub of the cam approximately 180° and a lever for actuating said cam.

9. A nut cracker, comprising a stationary jaw and a coöperating movable jaw, said jaws being provided in their opposed faces with conical nut-receiving recesses or depressions which are stepped so that nuts of various sizes can be arranged between said jaws when they are opened, an operating cam for said movable jaw having a spiral thread that extends around the hub of the cam approximately 180° and which imparts

1 a fixed stroke to said movable jaw in both directions, and a lever for oscillating said cam back and forth.

10. A nut cracker, comprising a base portion 5 provided with a rigid jaw, a movable jaw slidingly mounted on said base portion, said jaws being provided in their opposed faces with conical nut-receiving recesses or 10 depressions which are stepped so that nuts of various sizes can be arranged between said jaws when they are opened, and an operating mechanism for said movable jaw which imparts a fixed stroke to same toward and away from said stationary jaw.

15. 11. A nut cracker, comprising a base portion provided with an integral stationary jaw, a movable jaw slidingly mounted on said base portion, said jaws being provided in their opposed faces with conical nut- 20 receiving recesses or depressions which are stepped so that nuts of various sizes can be arranged between said jaws when they are opened, an operating cam arranged in a recess in said movable jaw and having a spiral 25 thread of approximately 180° that projects into an inclined groove in said base portion, an operating lever for said cam, and a shank on said operating lever that is journaled in said movable jaw and which forms a support 30 port for said operating cam.

35. 12. A nut cracker, comprising a base portion provided with an integral stationary jaw, a movable jaw slidingly mounted on said base portion, said jaws being provided in their opposed faces with stepped nut-receiving recesses or depressions which are so formed that nuts of various sizes can be arranged between said jaws when they are opened, an operating cam arranged in a recess 40 in said movable jaw and having a spiral thread of approximately 180° that projects into an inclined groove in said base portion, an operating lever, and a shank on said operating lever that is journaled in said movable jaw and which forms a support for 45 said operating cam, said cam being securely connected to said shank and the hub of the cam being so proportioned that it prevents the shank on said lever from moving out of 50 engagement with the bearings provided for same in said movable jaw.

13. A nut-cracker, comprising a base portion provided with a stationary jaw, a movable jaw slidingly mounted on said base por-

tion and provided with a pocket, a screw 55 cam arranged in said pocket, said base portion having an inclined groove for receiving the thread on said cam, an operating lever having a shank equipped with cylindrical portions that are journaled in the side walls 60 of said pocket and also having an intermediate portion of non-circular shape in cross section that fits in a bore of corresponding shape formed in the hub of the cam, and a retaining device passing transversely 65 through the hub of the cam and through said shank.

14. A nut cracker having a base portion that is substantially I-shaped in cross section and which is provided with an integral 70 hook-shaped part that projects downwardly from same, a clamping screw carried by said hook-shaped part, an integral jaw projecting upwardly from said base portion, a movable jaw slidingly mounted on said base 75 portion and provided at its lower end with flanges that coöperate with the upper flange of said base portion and hold said jaw in an upright position, an operating lever having a shank that is journaled in said movable jaw, and a screw cam securely connected to said shank and arranged with its thread in engagement with an inclined groove in the upper flange of said base portion.

15. A nut cracker, comprising a base portion provided with a stationary jaw, a movable jaw slidingly mounted on said base portion, coöperating means on said jaws for positioning nuts of various sizes when the jaws 90 are opened, a screw cam oscillatingly mounted in said movable jaw and provided with a thread that extends around the hub of the cam approximately 180°, said base portion having an inclined groove for receiving 95 the thread on said cam, an operating lever for actuating said cam, and stops on said cam that coöperate with said base portion for limiting the rotary movement of said cam in opposite directions.

100 In testimony whereof I hereunto affix my signature in the presence of two witnesses, this eighth day of April 1915.

WALTER O. McDANIEL.
